UNITED STATES PATENT OFFICE

148,443

DESIGN FOR A PIN OR SIMILAR ARTICLE

Edmund Jacob Richter, Moulton, Tex.

Application November 15, 1946, Serial No. 134,803

Term of patent 3½ years

(Cl. D45—19)

To all whom it may concern:

Be it known that I, Edmund J. Richter, a citizen of the United States, residing at Moulton, in the county of Lavaca and State of Texas, have invented a new, original, and ornamental Design for a Pin or Similar Article, of which the following is a specification, reference being had to the accompanying drawings, forming a part thereof.

I claim:

The ornamental design for a pin or similar article, as shown.

EDMUND JACOB RICHTER.
